UNITED STATES PATENT OFFICE.

FREDERICK D. PITTS, OF KANSAS CITY, MISSOURI, ASSIGNOR TO IRVING-PITT MANUFACTURING COMPANY, OF KANSAS CITY, MISSOURI, A CORPORATION OF MISSOURI.

LOOSE-LEAF BINDER AND THE MAKING OF SAME.

Application filed September 30, 1921. Serial No. 504,267.

To all whom it may concern:

Be it known that I, FREDERICK D. PITTS, a citizen of the United States, residing at Kansas City, in the county of Jackson and State of Missouri, have invented a certain new and useful Improvement in Loose-Leaf Binders and the Making of Same, of which the following is a specification.

My invention relates to improvements in loose leaf binders, and the making of same.

One of the objects of my invention is to provide a loose leaf binder of the type having two leaf-clamping members, one having leaf-supporting posts attached thereto and the other being slidable on said posts, with novel means carried by the slidable member for clampingly engaging the posts so as to permit the slidable member to move in one direction but holding it from moving in the opposite direction.

A further object of my invention is the provision of clamping means of the kind described which is simple, cheap to make, easy to operate and which is efficient in operation.

Another object of my invention is the provision of a simple and reliable post-clamping member and cheaply made efficient means for supporting the same.

My invention provides still further a novel leaf clamping member formed into a tube with interlocking edges and integral pintle barrels, and the method of making the same.

The novel features of my invention are hereinafter fully described and claimed.

In the accompanying drawings, which illustrate the preferred embodiment of my invention,

Fig. 1 is a vertical sectional view on the line 1—1 of Fig. 3 of a loose leaf binder embodying my improvements.

Fig. 2 is a top view of the same, partly in plan, partly in horizontal section and partly broken away,

Fig. 3 is a plan view, partly broken away, of a binder provided with my improvements.

Fig. 4 is an enlarged perspective view of one of the fulcrum supports of the post-clamping members.

Fig. 5 is an enlarged cross section of the slidable leaf-clamping member and one of the posts on which it is mounted, on the line 5—5 of Fig. 1, the post-clamping member

being shown in the post-clamping position, 55 the post being partly broken away.

Fig. 6 is a view similar to Fig. 5, the post-clamping member being shown in the release position.

Fig. 7 is an enlarged vertical sectional view on the line 7—7 of Fig. 6.

Fig. 8 is a perspective view of one of the post-clamping members.

Fig. 9 is a perspective view of the tubular portion of the upper leaf-clamping member in inverted position.

Fig. 10 is a perspective view of the clamp-releasing plate removed from the binder.

Fig. 11 is a detail cross-section of the upper leaf-clamping member through the cover hinge.

Similar reference characters designate similar parts in the different views.

1 designates a leaf-clamping member of an ordinary type having secured thereto two 75 posts 2, arranged to support detachable loose leaves 3, and having slidably mounted thereon a leaf-clamping member 4, preferably comprising a sheet of metal formed into a flattened tube and having its meeting edges 80 interlocked with each other, each edge being provided, preferably, with dove-tail-shaped recesses 5 and similarly shaped projections 6, fitted respectively in the recesses 5 of the opposite edge. One of said meeting edges 85 is provided with laterally extending projections formed into pintle barrels 7, in which is mounted a pintle 8, which is mounted in the adjacent portions of a cover member 9, Figs. 2 and 3.

The clamping member 4 is provided with two holes extending therethrough and designated by 10, in which the posts 2 are adapted to be slidably fitted.

The clamping member 4 may have fitted 95 on its ends respectively two caps 11.

Mounted in the tubular clamping member 4 respectively adjacent to the holes 10 are two supports, each comprising, preferably, a U-shaped plate 12, having its horizontal bottom portion rigidly secured to the inner side of the bottom of the member 4, and provided between its arms with an upstanding arm 13, the upper end of which has two shoulders 14, at opposite sides of an upwardly extending projection 15, which with the shoulders 14, Fig. 4, forms a fulcrum seat on which is pivotally mounted an angular

post-clamping member comprising a plate 16, the angle portion of which is pivotally seated on the shoulders 14, and which is provided with a hole 17, in which the projection 5 15 is loosely fitted.

The plate 16 is provided with means for clampingly engaging the adjacent post 2, comprising, preferably, the inner inclined portion of the plate having a hole 18, in 10 which the adjacent post 2 is adapted to loosely fit, when the plate 16 is forced from an inclined clamping position, shown in Fig. 1, toward a horizontal position. In the inclined clamping position the pressure of the 15 leaves 3 on the member 4, or any upward pull on the latter will cause the post-clamping members or plates 16 to clampingly engage the posts 2, and will hold the member 4 from upward movement, but will swing 20 upwardly sufficiently at its clamping end to permit the member 4 being forced downwardly.

For yieldingly holding the post-clamping member 16 in the clamping position shown 25 in Fig. 1, there is provided a vertical coil spring 19, the lower end of which is mounted in a hole 20, in the supporting member 12, and resting on the member 4, and the upper end of which bears against the member 16 30 at the left side of the arm 13, as viewed in Figs. 1 and 7, the member 16 being provided with a downwardly extending projection 21, Fig. 7, which extends into the upper end of the spring 19, and retains the 35 latter in operative position.

For manually releasing the post-clamping members from clamped engagement with the posts 2, to permit the free sliding movement upwardly of the member 4, on the 40 post, suitable means may be provided, such as a longitudinal plate 22, Figs. 1, 2 and 10, which is longitudinally slidable in the member 4, and which at one end is provided with a longitudinal slot 23, adapted to receive therethrough one of the posts 2, and which adjacent to the other end is provided with a longitudinal slot 24, adapted to receive therethrough the other post 2.

The end portion of the plate 22 having the 50 slot 23 is provided with two inclined cam surfaces 25 adapted to engage the under side of the clamping portion of the adjacent post clamping member 16, and to force the latter to the release position shown in Figs. 6 and 55 7, when the plate 22 is slid to the left, in Fig. 1, to a pre-determined release position.

The other end portion of the plate 22 is provided with two similarly upwardly and outwardly inclined cam surfaces 26, which 60 serve as cams for engaging the under side of the adjacent member 16, to force the latter to the release position simultaneously with the movement of the other member 16, to the release position.

65 For sliding the member 22 back and forth,

it has rigidly secured to it a finger piece 27, which extends through and is slidably in a slot 28, provided in the top of the member 4.

In the operation of my invention, after the leaves 3 have been mounted on the 70 posts 2, the clamping member 4 is slid downwardly on said posts, with the member 22 in the position shown in Fig. 1. When the clamping member 4 is clamped against the leaves 3, the springs 19 will force the members 16 into clamped engagement with the posts 2, and will prevent upward movement of the member 4 on the posts. To release the members 16, the member 22 is slid by means of the finger piece 27 to the position 75 shown in Fig. 7, at which time the cams 25 and 26 will have engaged and swung the members 16 to the release position, thereby permitting the member 4 to be slid upwardly off from the posts 2. When the 80 member 22 is restored to the position shown in Fig. 1, the member 4 may again be held in the clamping position when slipped onto the posts 2, by the members 16, engaging the latter.

In the making of the clamping member 4, dove-tail shaped recesses 5, Fig. 9, are first cut in opposite edges of the plate, one of the meeting edges having formed in it projections 6 and projections for the pintle barrels, the other meeting edge having formed in it recesses 29, Fig. 9, corresponding in width and depth to the width of the last-named projections and to the thickness of the plate. The barrels 7 are then formed 90 of said projecting portions of the plate, after which the plate is formed into a tube of desired shape with the dove-tail projections 6 of one meeting edge fitted in the recesses 5 of the other meeting edge and the barrel 100 projections fitted in the recesses 29 respectively, the dove-tail projections 6 having their outer surfaces flush with each other. A tube thus formed with interlocking dove-tail portions is very strong and cheaply 110 made.

I do not limit my invention to the structure shown and described, as many modifications, within the scope of the appended claims, may be made without departing from 115 the spirit of my invention.

What I claim is:—

1. In a binder, a leaf-clamping member having a hole therethrough adapted to have 120 slidably mounted therein a leaf supporting post, a plate secured to said leaf-clamping member and having an arm provided at one end with a projection, a post clamping member fulcrumed on said arm and having a hole into which said projection extends, and having a hole therethrough adapted to receive 125 said post, and arranged to be swung to a position in which it will clamp said post and hold the leaf-clamping member from moving in one direction on the post, but permit- 130

- ting its movement in the opposite direction, a spring arranged to swing the post-clamping member to the clamping position, and a 5 slideable member mounted on the leaf-clamping member and having means when moved to a predetermined position to move the post-clamping member from the clamping position, substantially as set forth.
2. In a binder, a leaf-clamping member 10 having a hole therethrough adapted to receive therein a slideable post, a fulcrum member secured to said member and having a hole, a post-clamping member having a hole therethrough adapted to receive said post and fulcrumed on said fulcrum member and provided with a projection, a coil spring fitted in the hole in the fulcrum member and supported by said leaf-clamping member and into which the projection of the post-clamping member extends and arranged to swing the post-clamping member to a position in which it will clamp said post and hold the latter from movement in one direction but permitting it to move in the other direction, and a slideable member mounted on the leaf-clamping member and movable to and from a position in which it will engage and move the post-clamping member from the clamping position, substantially as set forth.
3. In a binder, the combination with a leaf-supporting post, of a leaf-clamping member slideable thereon, a support carried by the clamping member and having a shoulder and a projection extending from said shoulder, a post-clamping member pivotally supported on said shoulder and having a hole into which said projection extends and which has engagement with said post such that it will clamp the post and hold the leaf-clamping member from sliding on the post in one direction but will permit it to slide in the other direction, a spring for normally forcing the post clamping member to the clamping position, and manually operated means for forcing the post-clamping member from the clamping position, substantially as set forth.
4. In a binder, the combination with a leaf-clamping member, two leaf-supporting posts carried thereby, a leaf-clamping member slideable on said posts, two supports carried by the slideable member, each having a shoulder and a projection extending from said shoulder, two post-clamping members respectively pivotally supported on said shoulders and having respectively holes into which said projections respectively extend, said post-clamping members having means for engagement respectively with said posts which permits the slideable member to move in one direction, but which will clampingly engage said posts when the slideable member is moved in the other direction, means for normally forcing said post-clamping mem- 55 bers to the clamping position, and manually operated means for moving the post-clamping members from the clamping position, substantially as set forth.
5. In a binder, the combination with a leaf-clamping member and two posts carried thereby, of a leaf-clamping member slideable on said posts, two supports on said slideable member, each having a shoulder and a projection extending from said shoulder, two post-clamping members respectively pivotally supported on said shoulders and having holes into which said projections respectively extend and having means for engagement with said posts respectively which permits movement of the slideable member in one direction, but which will clampingly engage said posts and hold the slideable member from movement in the opposite direction, resilient means for normally forcing the post-clamping members to the clamping position, and a manually slideable member on the slideable leaf-clamping member having means, when slid from a release to an operative position, for a simultaneously moving the post-clamping members from the clamping position, substantially as set forth.
6. In a binder, the combination with a leaf-clamping member and two posts carried thereby, of a leaf-clamping member slideable on said posts, two supports on said slideable member, each having a fulcrum seat, two post-clamping members respectively pivoted on said seats and held by said supports from sliding movement thereon and having means for respectively engaging said posts in a manner such that they will clampingly engage said posts respectively and hold the slideable member from movement in one direction but will permit its movement in the opposite direction, two springs for respectively forcing the post-clamping members to the clamping position, and a member manually slideable on the slideable leaf-clamping member having two cams arranged to engage and respectively simultaneously move said post clamping members from the clamping position, when the manually operated member is moved to a pre-determined position, substantially as set forth.
7. In a binder, the combination with a leaf-binding member and two posts carried thereby, of a leaf-clamping member slideable on said posts, two supports on said slideable member, each having a seat provided with a projection, two post-clamping members respectively pivoted on said seats and having holes into which said projections respectively extend and provided respectively with portions inclined from perpendicular relation to said posts and respectively bearing against said posts and arranged to clampingly engage the latter and to hold the slideable member from movement in one direction, but permitting its movement in the

opposite direction, two coil springs respectively held in operative position by said supports and respectively forcing said post-clamping members to the clamping position, and manually operated means for simultaneously moving said post-clamping members from the clamping position, substantially as set forth.

8. A leaf-clamping member of a loose leaf binder comprising a metal sheet formed into a tube having interlocking meeting edges and having extending from one of the meeting edges a projection formed into a pintle tube, substantially as set forth.

15 9. A leaf-clamping member of a loose leaf binder comprising a metal sheet formed into a tube with the meeting edges dovetailed into each other and having extending from one of the meeting edges a projection formed into a pintle barrel, substantially as set forth.

20 10. In post-clamping means of a loose leaf binder, a supporting member having an arm provided with a projection, and a post-clamping member pivotally mounted on said arm having two holes for respectively receiving said projection and a leaf-supporting post, substantially as set forth.

25 11. In post-clamping means of a loose leaf binder, a supporting member having a hole and having an arm provided with a projection, a post-clamping member pivotally seated on said arm and having a hole

35 into which said projection extends and having means for clampingly engaging a leaf-supporting post, and a coil spring fitted in said hole and bearing against said clamping member and arranged to force the latter to a clamping position, substantially as set forth.

40 12. The method of making a tubular clamping member of a binder consisting in cutting in opposite edges respectively of a flat metal plate, recesses and projections of like width, then forming the projections into 45 pintle barrels, and then forming the plate into a tube with the meeting edges abutting against each other and the barrel projections fitted in said recesses, substantially as set forth.

50 13. The method of making a tubular clamping member of a binder consisting in cutting in opposite edges respectively of a flat metal plate, dove-tail projections and recesses of like form and size and other projections and recesses of like width, forming the other projections into pintle barrels, and then forming the metal plate into a tube with the dovetail projections respectively fitted in the dovetail recesses of opposite edges and with the barrel projections fitted in said other recesses, substantially as set forth.

55 In testimony whereof I have signed my name to this specification.

FREDERICK D. PITT.
